(57) **CLAIM**

The ornamental design for a projection story machine, as shown and described.

DESCRIPTION

FIG. 1 is a front, top perspective view of a projection story machine, showing our new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and

FIG. 8 is a bottom plan view thereof;

FIG. 9 is another perspective view of the projection story machine, shown in an alternate position; and,

FIG. 10 is an enlarged view of detail "10" identified in FIG. 1.

The dashed broken lines in the figures illustrate portions of the projection story machine that form no part of the claimed design. The dash-dot-dash broken lines in FIGS. 1 and 10 depict the bounds of the enlarged views and form no part of the claimed design.
